SELF-PRIMING CENTRIFUGAL PUMP

William J. Regar, Tampa, Fla.

Application December 5, 1938, Serial No. 244,020

1 Claim. (Cl. 103—113)

This invention relates to that type of centrifugal pump in which a priming water reservoir provides water for circulation within the pump after it is started, and it has for its primary object to provide an eductor jet to draw air rapidly out of the suction line.

Another important object of the invention is to eliminate a great deal of friction by causing the flow of water through the pump to be in as direct a line as possible, and to be in the same direction as the movement of the impeller blades.

A further object of the invention is to provide a construction in which expensive castings are not necessary but which may be assembled from drawn steel tubing and sheet metal by welding processes, thus lowering the cost of production.

In the drawing illustrating a preferred construction, Figure 1 is a vertical sectional view in the planes indicated by the broken line I—I of Fig. 2 and Fig. 2 is a vertical sectional view in the planes indicated by the broken line II—II of Fig. 1.

The priming water reservoir 1 has a discharge port 2 located near its top and has the pump case 3 for the rotating impeller 4 supported inside the reservoir near the front surface. A closure plate 5 secured to the reservoir case has a central passage 6 for the impeller shaft 7 provided with any suitable packing means 8. The pump case has an outlet 9 in its periphery, preferably near the bottom through which the water is thrown by the impeller and has an inlet 10 offset to one side of the axis of the impeller shaft. The suction pipe 11 extends from near the top of the reservoir 1 downward to the inlet 10 so that water entering the pump case flows in the direction of movement of the rotating impeller blades in almost a direct line toward the outlet 9. A swinging check valve of the ordinary type is shown at the point where the pipe 11 is connected to the pipe 13 leading from the source of supply.

A baffle plate 14 extends from the front wall of the reservoir below and in the rear of the outlet 9 across the reservoir to within a short distance of the rear wall. The front end of this baffle plate directs the water leaving the outlet 9 against the curved wall of the reservoir leading upward to the outlet port 2. A portion of the water will be driven around the reservoir until

it is checked by the baffle plate. A tube 15 has its open lower end directed toward the oncoming water, while its upper end discharges into the pipe 11 at a little distance from the inlet 10.

Water rushing up the tube will enter the pipe 11 as a jet which will act at every turn of the propeller to carry some of the air through the outlet 9. Within a few seconds after starting, the air in the suction pipe will all be removed and the pump will then run as an ordinary centrifugal pump. The location of the lower end of the tube 15 near the bottom of the reservoir makes it possible to operate the pump with a minimum quantity of priming water.

A clean-out plug 16 near the bottom of the reservoir affords easy access to the space behind the baffle plate.

It will be seen that the construction shown and described can readily be made from tubing and sheet metal by simple welding and that there are no difficulties in the assembly. The pipe 11 will ordinarily have only a single curve and by arranging the inlet at one side of the axis of the impeller and delivering the water at an angle such that its direction of movement will correspond with the downward movement of the blades of the impeller, there will be very little friction as compared with the usual arrangements.

The illustration and description are to be taken as merely those of a single embodiment of the invention, since many changes in size, form, proportion, and arrangement of parts may be made by those skilled in the art without departure from the invention as claimed.

I claim:

A self-priming centrifugal pump having a priming liquid reservoir, an impeller case having an outlet near its bottom discharging into said reservoir, a suction pipe delivering liquid into the impeller case, a baffle within the reservoir at its lower end to check rotation of liquid therein, and a tubular conduit having its lower end within the reservoir adjacent to the baffle and its upper end arranged to discharge liquid into the suction pipe at a little distance from its inlet into the impeller case.

WILLIAM J. REGAR.
